UNITED STATES PATENT OFFICE

EDWARD B. HOUGH, OF PROVIDENCE, RHODE ISLAND

CIGARETTE CASE

Application filed July 24, 1928. Serial No. 295,111.

The invention relates in general to containers and, more particularly, to cigarette cases.

It is desirable, in a cigarette case, that the cigarettes be held therein gently but firmly to prevent shaking about while the case is carried on the person, and also that the construction permit easy filling of the case and easy dispensing of the cigarettes, when desired. These advantages and others, which will appear as the description proceeds, are attained by the present invention.

According to one embodiment of the invention, the cigarette case is made up of a base cover having a bottom with a separate frame connected thereto and also a top cover hingedly connected to the frame. The frame is provided, at one side, with a ramp or cigarette-dispensing surface by which an individual cigarette may be dispensed by pushing it lengthwise until its end projects beyond the edge of the case. A suitable spring pressed holder is provided to gently but firmly hold the cigarettes in position. A suitable catch arrangement is also provided comprising a catch member adapted to engage the top cover, a spring bar suitably riveted to the frame and a finger piece passing through the frame by which the catch is operated.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is a plan view showing the case in open position;

Fig. 2 is a section on the line 2—2 of Fig. 1;

Figs. 3, 4 and 5 are details taken on the lines 3—3 of Fig. 2, and 4—4 and 5—5 of Fig. 1 respectively;

Fig. 6 is a perspective of the catch bar;

Fig. 7 is a perspective of the catch elements in assembled relation;

Fig. 8 is a section on the line 8—8 of Fig. 1;

Fig. 9 is a section on the line 9—9 of Fig. 3;

Fig. 10 is a perspective of the ramp detached;

Fig. 11 is a detail of the holder member; and

Fig. 12 is a detail of the frame member.

In the following description and in the claims parts will be identified by specific names for convenience, but they are intended to be as generic in their application to similar parts as the art will permit.

Like reference characters denote like parts in the several figures of the drawings.

In the drawings accompanying and forming part of this specification, a practical commercial embodiment of the invention is shown, but as such illustration is primarily for purposes of disclosure, it will be understood that the structure may be modified in various respects without departure from the broad spirit and scope of the invention as hereinafter defined and claimed.

Referring now to the drawing, the cigarette case according to the invention comprises a top cover 1 and a base cover 2 hingedly connected together. The base cover comprises a bottom 3 of generally rectangular shape and made of sheet metal having its edge beveled as at 4 and turned in to form a bead 5 as shown, and a generally rectangular frame 6.

The frame 6 is made in the form of a continuous upright wall 7 having an inturned lower flange 8. The sides of the frame are provided with stamped out projections 9 (Fig. 9) engaging under the inturned edge of the bead 5 when the lower flange 8 seats against the bevel portion 4 to hold the frame 6 and bottom 3 in assembled relation.

The top cover 1 is of a construction similar to that of the bottom 3 and has its edge bent to form a bevel portion 10 and turned in to form a bead 11. The bead 11 on one side has a plurality of recesses 12 (Fig. 4) for a purpose hereinafter described.

The back side of the frame is provided with two indented portions 13 in which are dis-

posed two hinge knuckles 14, the hinge knuckles being riveted to the upright wall 7. The hinge knuckles 14 are disposed in the recesses 12 in the bead 11 and a single pintle 15 (Fig. 1) passes through each knuckle and seats in the bead 11 in the top cover and is suitably secured thereto as by solder. The pintle 15 is in the form of a tube through which passes a spring wire member 16, one end 18 of the spring member being bent out against the bevel portion 10 of the top cover and the other end 19 being suitably bent on the upstanding wall 7 of the base cover. This construction is such as to cause the top cover to normally tend to assume an open position.

Secured to one transverse side member of the frame 6 is a gently-sloping, cigarette-dispensing ramp or plate 17 extending from the bottom 3 up to the reduced edge 20 of the up-right wall 7 and suitably secured in position. The ramp 17 has a depending flange 21 having a plurality of tongues 22, the upright wall 7 having apertures through which the tuyères pass, the tongues being bent over after passing through the wall.

To yieldably hold the cigarettes in the base cover, a holder 23 is provided. This holder is generally of U-shape having an open skeleton cross bar 24 and flat end bars 25 connected thereto. Each end bar 25 is bent to form a flat ear 26 having a notch 27 and pivot projection 28 which is adapted to enter a pivot hole 29 in the frame member. A suitable spring wire 36 is placed, on each side of the frame member, working in the notches 27. The spring members 36 pass behind the frame member between it and the inturned edge of the bottom, through the long holes 37.

It will be seen that the springs 36 will normally press the holder 23 against the cigarettes, but if the holder is raised beyond a certain position, as for instance, to the position shown in Fig. 2, the springs will hold the holder in this position. This expedient is convenient when it is desired to fill the case with cigarettes.

The catch is made up of a U-shaped finger piece 30 and a spring strip 31. The spring strip has a projection 32 which is adapted to engage the inturned edge of the top cover 1 when the case is closed. The spring strip 31 also has openings 33 to accommodate the projecting tongues on the ends of the finger piece 30, the projections being riveted or clinched over to secure the finger piece to the spring member. The spring member 31 is suitably riveted to the upright wall 7 of the front side of the frame 6 as clearly shown in Fig. 7.

In order to fill the case with cigarettes, the holder is lifted to its upper position, shown in Fig. 2, where it is locked by the springs 36. The compartment in the base cover is then readily accessible and the case can be easily filled with cigarettes. After the case is filled, the holder is moved to the position shown in

Fig. 1 where it gently and yieldably holds the cigarettes in the base cover. When it is desired to dispense a cigarette, a cigarette may be engaged at the end remote from the ramp 17 and pushed lengthwise, the inclined surface 17 allowing the cigarette to ride over the edge of the base cover. The position and resilience of the holder allows this action without any detrimental effect on the cigarettes.

Thus a cigarette case has been provided which is of relatively large capacity and yet which is thin and convenient to carry about the person. The case may be filled with utmost ease and without mutilating the cigarettes in any way. Similarly, the cigarettes may be removed one at a time with utmost ease and without mutilating them. The cigarettes are gently but firmly held in the case so that they can not be damaged by carrying about on the person. Furthermore, the parts may be made rugged and comparatively inexpensively and the case is easy to assemble. The arrangement is such that the device is not likely to get out of order but will have a long and useful life, giving pleasing and efficient service to the user.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. In a cigarette case, a base cover comprising a bottom having an inwardly projecting flange, a frame having a lateral flange overlying said bottom and an upstanding wall, said upstanding wall having a part reduced in height on one side, a cigarette-dispensing ramp gently sloping from the top of said reduced part to said bottom and having a depending flange disposed inside said reduced part, said reduced part having apertures, said depending flange having tongues passing through said apertures and bent over on the outside, and a top cover hingedly connected to said base cover and fitting over said upstanding wall.

2. In a cigarette case, a base cover and a top cover, said base cover comprising a bottom, a separate rectangular frame held in said bottom, a U-shape holder having opposed pivots, said frame having opposed pivot openings in which said pivots fit, substantially straight springs secured to said frame and bearing on said holder to press it against the cigarettes.

3. In a cigarette case, a base cover and top cover, said base cover comprising a bottom having an inwardly projecting flange, a separate frame held by said flange, said frame having pivot openings, a U-shape holder hav-

ing pivots fitting in said openings, said holder having small ears provided with notches, said frame having holes, substantially straight wire springs held between said frame and the bead formed by said inwardly projecting flange, said springs projecting through said holes and disposed in said notches, whereby said holder is yieldably pressed against the cigarettes and is locked in raised position.

10 4. In a cigarette case, a base cover and a top cover, said base cover comprising a bottom having an inwardly projecting flange, a separate frame held by said flange, a U-shape holder, means pivoting said holder to said frame, said holder having small ears provided with notches, said frame having holes, wire springs held between said frame and the bead formed by said inwardly projecting flange, said springs projecting through said holes and 20 disposed in said notches, whereby said holder is yieldably pressed against the cigarettes and is locked in raised position.

In testimony whereof I have hereunto set my hand.

25 EDWARD B. HOUGH.
